UNITED STATES PATENT OFFICE.

THOMAS W. JENKINS, OF PHILADELPHIA, PENNSYLVANIA; JENNIE A. JENKINS
EXECUTRIX OF SAID THOMAS W. JENKINS, DECEASED.

ELEVATOR INTERLOCKING DEVICE.

1,336,748.

Specification of Letters Patent.

Patented Apr. 13, 1920.

Application filed July 13, 1918. Serial No. 244,680.

To all whom it may concern:

Be it known that I, THOMAS W. JENKINS, a citizen of the United States, residing at Philadelphia, county of Philadelphia, and 5 State of Pennsylvania, have invented a new and useful Improvement in Elevator Interlocking Devices, of which the following is a full, clear, and exact description, reference being had to the accompanying drawings, which form a part of this specification.

My invention relates to that class of mechanism known as safety stops for elevators by means of which the gates at the landings of the elevator shafts are locked 15 in closed position and prevented from being opened at all times except when the elevator in the shaft has been brought to rest registering with a landing, in which case the gate of said landing is free to open. 20 It also precludes the possibility of further operating the car until said gate has been closed again.

Such locking safety means is old and well known in the automatic elevator interlocking art, and a well known, simple means 25 therefor will be described and illustrated in connection with my invention.

As a further step it is desirable, and in some States is even made mandatory by 30 statute or by orders of elevator inspecting bureaus, that there be present, in connection with such locking means, an arrangement for rendering said means inoperative, upon occasion, by the elevator operator, whereby 35 the car may be operated in the shaft while the gate is in open position.

The object of my invention is to provide 40 this further means in connection with the car and gate locking mechanism, and comprises certain apparatus, located on the car within reach of the operator, whereby by pulling a lever the result will be accomplished.

I will now proceed to describe in detail 45 a device embodying my invention, in connection with the accompanying drawings, in which—

Figure 1 is a vertical sectional view of an 50 elevator in connection with a landing. Fig. 2 is a section on line 2—2 of Fig. 1 showing in elevation the side of the elevator containing the operator's handles.

Fig. 3 is a face view of the gate lock at the landing.

55 Fig. 4 is a section on line 4—4 of Fig. 5.

Fig. 5 is a plan view of the mechanism on line 5—5 of Fig. 4.

Fig. 6 is a section on line 6—6 of Fig. 5.

Fig. 7 is an enlarged detail view of a portion of the mechanism on the elevator. 60

Inside the elevator shaft, at each landing, there is a locking plate *a* carrying the locking mechanism for the gate at that landing. *x* represents the gate, *y* the floor of the elevator car and *z* the landing. 65

A bar *b*, connected with the gate, extends downward over the face of plate *a*, where it engages a locking wheel *c* provided with a cam face *d*. The locking wheel is prevented from turning to free bar *b* and allow the 70 gate to open, by a stop *e* on said wheel contacting with the toe *f* of a pivoted plate *g* normally held in the path of the stop by the action of a spring *h*, see Figs. 3, 4 and 5.

Thus, the gate is locked in closed position 75 at every landing in the shaft and a gate may be unlocked only when the elevator is brought to a stop in the shaft so that its floor registers with the landing or floor level of that gate.

Beneath the floor *y* of the elevator car 80 there is a depending angle frame *i* which carries the device for unlatching the lock. A three-armed lever *q* is centrally pivoted to frame *i*, one of whose arms operates a 85 bolt *j* in alinement with the portion of plate *g* on the locking plate that covers spring *h*. The opposite arm of lever *q* operates a bolt *k* in alinement with a beveled cam plate *m* pivoted to the locking plate at *n* and 90 adapted to be swung outward of the plate by cam *d*.

Bolt *k* carries a beveled shoe *o* for contacting with cam piece *m*. Shoe *o* is carried on a short arm which is pivotally 95 mounted at *p* to frame *i*. The outward movement of the shoe *o* is limited by an adjustable stop bolt *r* so as to just clear cam plate *m*, which is held close against the locking plate by a spring *s*.

A spring *t* between lever *q* and frame *i* acts to normally hold bolt *k* and shoe *o* out against stop *r*. In this position bolt *j* just clears the portion of plate *g* with which it alines, so that the elevator may pass up and 105 down its shaft freely without acting upon any of the mechanisms upon plates *a* at the various landings.

The elevator operating wheel *u* is provided with an orifice *v* in its hub, so located 110

that when said wheel is turned to stopped position orifice *v* is directly underneath and in vertical alinement with a rod *w* adapted to be entered therein.

5 Rod *w* extends downward through the floor *y* of the elevator and is actuated by a short arm 10 attached to a rock shaft 11 carried beneath said floor. Another arm 12 on this rock shaft is connected by a link 13 10 with the third arm of lever *q* carrying bolts *j* and *k*.

As described, the parts of the mechanism are so arranged that when the elevator is brought to a stop at a landing the gate may 15 be opened as follows. By pushing the gate to the right, Figs. 1 and 3, locking wheel *c* is turned bringing cam face *d* down behind cam plate *m*. This turns the cam plate outward against spring *s*, and presses in shoe 20 *o* and bolt *k*, which in this position of the elevator are registering therewith. This turns lever *q* against the action of spring *t* and presses bolt *j* outward, which in turn contacts with pivoted plate *g* and turns it 25 against the action of its spring *h*. In thus turning plate *g* its toe *f* is raised out of line with stop *e*, allowing locking wheel *c* to continue turning so as to release bar *b* of the gate and allow the latter to be freely opened.

30 In the turning of lever *q* the third arm, described as connected with link 13, turns rock shaft 11 and this in turn moves rod *w* upward into the orifice *v* in the hub of the operator's wheel *u*. This prevents turning of the 35 operator's wheel to move the elevator up or down and therefore prescribes that the elevator remains stationary at this landing until the gate is closed to retract cam face *d* and allow the mechanism to return to its 40 normal position.

It is seen that to allow of the foregoing operation the operator's wheel must be very exactly brought to the stopped position in which rod *w* and orifice *v* are in alinement. 45 Otherwise, the mechanism will lock and the gate cannot be opened.

In order to render this locking of the operator's wheel inoperative, in emergency, the following mechanism has been added. 50 A third short arm 14 is attached to rock shaft 11 and connected with a rod 15 which is extended vertically up through the floor of the elevator and into a glass-covered box 16, mounted on the side, within reach of the operator. Within this box, visible through the glass front, is a lever 17, the short arm of which is pivoted to the upper end of rod 15, and the longer, upstanding arm provides a handle by which the operator can nullify 55 the effects of the locking mechanism previously described.

In the normal working of the elevator, when it is brought to stop at a landing and the gate opened, the rock shaft 11 is turned counter-clockwise in Fig. 1, and rod 15 is

60 pulled down slightly, tipping the handle of lever 17 toward the wall. If this were kept from so tipping backward, or were pulled forward by the operator, the rock shaft could not turn as described to press rod *w* 70 upward into the orifice *v* in the hub of the operator's wheel to hold it from being turned. Thus, the car could be manipulated while the gate is open.

As the rock shaft is thus kept from being 75 turned to raise rod *w*, the three-armed lever *q* remains stationary or at least does not turn to press bolt *j* outward, and therefore this bolt does not project to interfere with any of the plates *g* at the various landings 80 and prevent the free passage of the car. Similarly, bolt *k* is not moved and therefore means is provided for keeping bolt *k* stationary and yet allowing cam face *d* to 85 occupy its active position behind cam plate *m*, as it does while the gate is open.

This means consists of a spring 20 interposed between bolt *k* and shoe *o*. The bolt may be recessed as shown in Fig. 7 and the shoe provided with a shank for entering the recess against the spring. Springs *t* and *u* therefore act against each other to normally hold lever *q* in central position with shoe *o* held pressed outward against its limiting stop *r*. Spring 20 is stiff enough to insure 95 that shoe *o* and bolt *k* normally act together to operate the locking devices described, but upon occasion the operator may break the glass of box 16, as with a convenient hammer 100 18 provided therefor, and pull upon handle 105 17 so as to compress spring 20 and allow the car to be operated.

Having now fully described my invention, what I claim and desire to protect by Letters Patent is:

1. The combination, with an elevator shaft containing a landing and a gate therefor, a car movable in the shaft and a controller in the car for governing its operation, of interlocking contrivances on the car and the shaft 110 by which the gate is locked when the car is not opposite thereto and the controller is locked when the gate, the car being opposite thereto, is opened, the interlocking contrivance on the car comprising a spring 115 which in the controller-locking operation positively transmits motion from one element to another, and a manually actuatable emergency device operable, when the gate is open, to actuate part of the interlocking 120 contrivance on the car to unlock the controller and compress the spring.

2. The combination, with an elevator shaft containing a landing and a gate therefor, of a turnable member, means on the gate 125 adapted as the gate is moved from its closed position to turn the turnable member, a cam adapted to be moved into operative position by said turnable member, a shoe, carried by the car, adapted to be actuated by said cam, 130

a pivoted lever, a spring between said lever and shoe, a link connecting said lever to a second pivoted lever, means adapted to lock the controller connected to said second lever, and manually operable means, connected to said latter lever, whereby said controller-locking mechanism may be released, while

the cam is in operative relation with the shoe, through the compression of said spring.

In testimony of which invention I have hereunto set my hand at Philadelphia on this 20th day of June, 1918.

THOMAS W. JENKINS.
